(57) CLAIM

The ornamental design for pants, as shown and described.

DESCRIPTION

FIG. 1 is a front elevational view of pants, showing my new design;

FIG. 2 is a rear elevational view thereof;

FIG. 3 is a right side elevational view thereof;

FIG. 4 is a perspective view thereof;

FIG. 5 is another front elevational view thereof; and,

FIG. 6 is another right side elevational view thereof.

The broken lines are for illustrative purposes only and form no part of the claimed design.

1 Claim, 6 Drawing Sheets
